Patented Jan. 27, 1970

216,517

BAR BELL WEIGHT

Harry M. Dorn, 1133 Broadway,
Flushing, N.Y. 11373

Filed Mar. 5, 1969, Ser. No. 16,060

Term of patent 14 years

Int. Cl. D21—03

U.S. Cl. D34—5

FIG. 1.

FIG. 2.

FIGURE 1 is a view of the bar bell weight seen from one side and the opposite side is identical with the side shown; and

FIGURE 2 is a view of the bar bell weight seen from the edge.

I claim:

The ornamental design for a bar bell weight, substantially as shown and described.
